UNITED STATES PATENT OFFICE.

PALMER D. WEEKS, OF NEW YORK, N. Y.

GARMENT HANGER.

1,415,747.

Specification of Letters Patent.

Patented May 9, 1922.

Application filed July 28, 1921. Serial No. 488,164.

To all whom it may concern:

Be it known that I, PALMER D. WEEKS, a citizen of the United States, and a resident of the city of New York, borough of Manhattan, in the county and State of New York, have invented a new and Improved Garment Hanger, of which the following is a description.

My invention relates to a garment hanger and aims to provide certain new and useful improvements in connection with a device of this character.

It is well understood that any number of garment hangers have been placed upon the market in which the parts were capable of manipulation to permit of the hangers being folded to occupy a minimum of space when not in use. However, most of these hangers have been relatively complicated in construction and have also been incapable of being manufactured at a nominal figure.

Further defects experienced have been that particularly with ladies' garments, few, if any, garment hangers have provided facilities for the support of skirts when not in use.

With this in mind my present invention aims to provide a garment hanger which shall be extremely simple in construction and be capable of being manufactured at a nominal figure.

A further object of this invention is the provision of a device of the character stated in which means will be provided permitting of a lady's garment such as a skirt being supported by the same and still further objects will appear from the annexed specification taken in connection with the drawings, which latter present one practical embodiment of the invention, and in which—

Figure 1 illustrates a hanger of my improved construction and showing the same in use;

Figure 2 shows the position which the parts assume when these parts have been manipulated to cause the hanger to occupy the minimum of space; and

Figure 3 is a plan view of the device as illustrated in Figure 2.

In these views it will be noted that the reference numerals 5 and 6 indicate bars which are pivotally secured one to the other preferably by means of the stem 7 of the hook 8.

With a view of preventing the bars 5 and

6 from swinging beyond certain limits it will be noted that I utilize a third bar 9, the ends of which are connected, one to each of the bars 5 and 6 by means of links 10.

Thus, as in Figure 1 the bars 5 and 6 are prevented from swinging to a position beyond that at which they would properly support the shoulder portions of garments, such as coats, vests, etc., and the bar 9 may serve to support trousers.

However, to provide means which will serve to permit of a skirt 11 being supported by this latter bar, it will be noted that bayonet slots 12 are formed in the lower edge of this latter bar and at points adjacent the end of the same. By this construction it is permissible for the user to introduce the loops 13 of the skirt through the constricted portions of each of the slots so that the same may be disposed within the edge portion thereof at which point this garment will be properly supported.

If it is now desired to fold the garment hanger this may be accomplished by simply swinging the bars 5 and 6 to a point at which they virtually lie in the same plane as in Figure 2. This is permitted by virtue of the links 10 which form a movable connection between the bar 9 and the bars 5 and 6 and when the latter bars have assumed the position indicated it will be obvious that as in Figures 2 and 3 the bar 9 may be swung to a position at which one of its side faces lies against the side faces of the bars 5 and 6 so as to form an extremely compact article.

Thus, all the objects in the preamble of the specification are accomplished and it will be further understood that numerous modifications of the structure might readily be resorted to without at least departing from the scope of my claim, which is—

A hanger of the character described comprising a pair of bars pivotally secured together at one end to a suspension hook, said hook being adapted to be collapsible flush to one side of either of said bars, an eye screw secured to the free end of each bar, eye screws secured to the ends of said third bar, and links interposed between the eye screw of the pivoted bars and the eye screw of the third bar so as to form a triangular frame having its lower member in pendulum with respect to the upper member.

PALMER D. WEEKS.
